SWITCH AND CIRCUIT BREAKER

Filed May 17, 1928

UNITED STATES PATENT OFFICE

KURT WILCKENS, OF PHILADELPHIA, PENNSYLVANIA, ASSIGNOR TO HEINMANN ELECTRIC COMPANY, OF PHILADELPHIA, PENNSYLVANIA, A CORPORATION OF PENNSYLVANIA

SWITCH AND CIRCUIT BREAKER

Application filed May 17, 1932. Serial No. 278,521.

My invention is designed to provide a switch and circuit breaker which automatically opens a circuit immediately upon the occurrence of an abnormal overload and automatically opens the circuit after a brief lag 5 upon the maintenance of a slight overload, but which will permit the brief flow of a harmless momentary overload of limited amount such as occurs when a motor or electrical appliance is cut in. If, however, the 10 overload of limited amount continues, the circuit is not only broken but the subsequent closure and maintenance thereof is prevented until the current is reduced to normal or the protected device has had an opportunity 15 to cool.

In the preferred embodiment of my invention, the circuit controlling switch blade is normally operable by a handle connected with the blade through links forming a toggle joint adapted to be broken to open the 20 switch by an armature actuated by electromagnetic force. The armature is so positioned relatively to the source of electromagnetic force as to be beyond the attractive 25 power of the magnetic field resulting from the passage through such source of normal current or of a limited overload, but is within the attractive power of the magnetic field resulting from the passage of an abnormal 30 overload. To prevent the maintenance of flow of a limited overload current, we provide thermostatic mechanism which, when heated by a sustained flow of excessive current, moves the armature into the zone of 35 attractive power of the magnetic field resulting from the passage of any overload. Consequently there is a lag in the operation of the device when the overload is of limited amount. Such lag affords a brief time for 40 the return of the current to normal without breaking the circuit, but if the current does not return to normal within the period allowed, the circuit is broken and cannot there- 45 after be maintained until the thermostatic device has cooled sufficiently to cause the removal of the armature from the attractive power of the magnetic field, thereby afford- 50 ing time for cooling the windings of the motor or the like.

The characteristic features and advantages of my improvements will more fully appear from the following description and the accompanying drawings in illustration thereof.

In the drawings, Fig. 1 is a transverse sectional view through a casing containing a switch and circuit breaker embodying my improvements, with part of the bracket supporting the operating parts broken away; Fig. 2 is a front elevation thereof with the 55 cover removed; Fig. 3 shows detached perspective views of switch blade members; Fig. 4 is a detached perspective view of the armature; and Fig. 5 is a diagrammatic wiring 60 diagram of the device.

As illustrated in the drawings, an insulating base 1, preferably housed within a casing 2 having an apertured hinged cover 3, has fixed thereto a bracket 4 from which depends a solenoid coil 5. A tube 6 is secured in 65 the center of the coil and is capped by an adjustable cap 7. An armature 8, having a non-magnetic nose piece 9, is movable longitudinally in the tube and its normal vertical position may be regulated by adjusting the 70 cap 7.

A blade carrier 10 is journaled on the pin 11 carried by the bracket 4 which contains a slot for the passage of the tail of the carrier, and a block 12 on the pin 11 is housed 75 between the bifurcations of the carrier and provides an anchorage for a bent spring 13 secured to the block by a pin or rivet 11'. The spring 13 projects upward beyond the carrier 10, and has fixed thereto a detachable contact 80 14. The outer end of the spring is positioned relative to the carrier 10 by a pivot 15 on which is journaled a U-shaped link 16 pivotally connected by a pivot 17 with a link 18. A pintle 19 connects the link 18 with a hub 85 20 provided with a handle 20' and journaled on the pin 21 carried by the bracket 4.

An arm 22 projecting from the link 18 is provided with a foot 23 disposed in alignment with the armature 8 when the switch is 90 closed. An ear 24 projecting from the link 16 has a locked set screw 25 threaded therein and adapted to contact with the link 18 so as to regulate the limit of movement of the members 16 and 18 toward the bracket 4. 100

A contact 26 fixed to the base 1 within the asbestos lined shield 27 is positioned for engagement by the contact 14 and is connected with a line terminal 28 through a suitable conductor 26' preferably recessed in the base 1.

A load terminal or bracket 29 fixed to the baseboard 1 has a conducting post 30 projecting therefrom on which is coiled a thermostatic conductor 31 comprising connected laminated sheets of metals welded together and having different coefficients of expansion. The end of the thermostatic device 31 projects through slots 7' in the cap 7 beneath the bottom of the armature 8, which normally rests thereon. The bracket 29 may be connected by a suitable conductor 29' with an appropriate load (not shown) from which a return wire runs to the terminal 32 of the neutral wire of the system. The thermostatic device 31 is connected with an end 5' of the coil 5, and the other end 5" of the coil is connected with a binding post 5a which is connected by the conductor 13' with the blade 13.

The hub 20 has a segment cut from the periphery thereof opposite the handle 20' to form stops 20a and 20b which engage with the web of the bracket 4 to limit the throw of the handle. The remaining peripheral segment of the hub forms a closure for the opening in the lid 3 in either position of the handle. Should the lid 3 be opened while the handle 20' is in the upper position it is thrown by the engagement therewith of the lid to the lower position indicated in dotted lines to open the switch.

Any desired number of circuit breakers may be mounted upon a base plate or panel, but preferably they are mounted in pairs connected with a single return wire, as shown in Fig. 2.

When a handle 20' is thrown to the upper position shown in full lines in Fig. 1, it acts through the hub and link mechanism described to rock the switch carrier 10 toward the base 1 against the action of the spring 13 and bring the contact 14 into engagement with the contact 26. The stop 20a and screw 25 are so positioned that when the switch is closed the axes of the pintles 21, 19, 17 and 15 are not in a straight line, the pintle 17 being slightly nearer to the bracket 4 than would be a corresponding point in a straight line connecting the pintles 21 and 15.

When normal current flows from the line it passes through the terminal 28, conductor 26', contact 26, contact 14, spring 13, conductor 13', binding post 5a, coil 5, flexible lead 5', thermostatic device 31, post 30, bracket 29, conductor 29', terminal 32 to ground. The load, return wire and non-magnetic nose 9 may be adjusted longitudinally in the bottom or magnetic portion of the armature 8 which normally lies below the portative force

of the magnetic field created by the passage of normal current through the coil 5; the device 31 having such conductivity that it is not heated or bent by the flow of normal current.

70

The portative force of the magnetic field resulting from a slight overload is insufficient to lift the armature 8 from its normal position at the bottom of the tube 6, but the continued flow of such overload through the member 31 heats the metals thereof and expands them unequally thereby causing the coiled portion thereof to elevate the projecting end. The magnetic portion of the armature 8 is thereby lifted into a more intense zone of the magnetic field of the coil 5, which attracts the armature and moves the non-magnetic nose 9 thereof against the foot 23 with sufficient force to break the joint between the links 16 and 18 by throwing the pin 17 beyond dead center and permitting the spring 13 to open the switch.

75

It will, therefore, be seen that a momentary relatively small overload, such as occurs in starting a motor or other electrical appliance, will not break the circuit until such overload has persisted for such period as is required to heat the device 31, which may be so adjusted as to move upward before damage is done to the insulation of the appliance being protected.

80

If the switch is closed while the part 31 is still heated and there is any overload, the attraction of the solenoid causes the armature to immediately break the toggle joint and open the switch.

85

When an abnormal overload occurs, such as results from a short circuit or static discharge, likely to cause immediate damage, the magnetic field created by the passage thereof through the coil 5 is sufficiently strong to immediately attract the armature 8 and cause it to break the toggle joint without awaiting the heating of the element 31.

90

Having described my invention, I claim:

110

1. A switch and circuit breaker comprising a switch, a toggle connected with said switch, a handle connected with said toggle, an armature for operating said toggle, a solenoid coil surrounding and actuating said armature and a bi-metallic thermostatic strip having a section movable toward and from a plane normal to the axis of said solenoid coil, said armature being positioned relative to said solenoid by the movement of said section.

115

2. A switch and circuit breaker comprising a switch, a toggle connected with said switch, a handle connected with said toggle, a core for operating said toggle, a solenoid coil surrounding and actuating said core and a coil of bi-metallic thermostatic metal having a fixed axial end and a free projecting end, said core being positioned relative to said solenoid by the movement of said free projecting end of said coil.

120

3. A switch and circuit breaker comprising a switch, a toggle connected with said switch, a handle connected with said toggle, a core for operating said toggle, a solenoid coil surrounding and actuating said core and a coil of bi-metallic thermostatic metal having a fixed axial end and a free projecting end, said core being positioned relative to said solenoid by the movement of said free projecting end of said coil.

125

130

3. A switch and circuit breaker comprising a switch and a fulcrumed handle, a springless toggle having its ends pivotally connected with said handle and switch, a core movable into engagement with said member to break said toggle, a solenoid coil surrounding and operating said core, a guideway extending axially of said coil at the opposite end thereof from said toggle, and a thermostatic member having a section housed in said guideway and movable therein toward and from said coil, for varying the position of said core relatively to said solenoid coil.
4. A switch and circuit breaker comprising a bracket having recesses at the ends thereof and an aperture between said recesses, a solenoid coil depending from said bracket and having an axial passage aligned with said bracket aperture, a slotted tube depending from said solenoid coil and having therein a core with a non-magnetic nose fixed thereon and normally occupying said axial coil passage, a coil of thermostatic metal having an axial end fixed and a projecting free end movable vertically in the slots of said tube to position said core relatively to said coil, a fulcrumed member oscillatable in one of said bracket recesses, a spring switch blade connected with said member, an oscillatory handle oscillatable in the other of said bracket recesses, and a toggle connecting said handle and member and comprising a bell-crank shaped member having one arm thereof disposed in the path of movement of the nose of said core, and a link pivotally connected with the apex of said bell-crank, said link having an extension preventing breakage in one direction in the joint between said bell-crank and link.
5. A switch and circuit breaker comprising a switch blade, a toggle for operating said switch blade and comprising a pair of links one of which is connected with said switch blade, a handle connected with the other of said links, a solenoid coil containing an axial passage in substantial alignment with the knee of said toggle, a core movable in said passage to break said toggle and having thereon a non-magnetic nose normally occupying the passage of said coil and projected therefrom by said core upon the excitation of said coil, a guideway extending axially of said coil and normally housing said core, and a thermostatic device having a section housed in said guideway and movable therein toward and from said coil for positioning said core relative to said coil.
6. A switch and circuit breaker comprising a switch blade normally biased to open position, a solenoid coil responsive to current in the circuit controlled by said blade and having an axial opening therein, a toggle adjacent to one end of said coil for holding said switch blade in closed position, a coil of bimetallic thermostatic metal having an axial
- end fixed adjacent to the end of said solenoid coil opposite to said toggle and having a free projecting end movable toward and from a plane normal to the axis of said solenoid coil, and trip means for operating said toggle and comprising an armature movable in said axial opening and a non-magnetic member between said toggle and armature, said armature being positioned by the free end of said thermostatic coil and actuated by the magnetic flux of the solenoid coil.
- In testimony whereof I have hereunto set my hand this 16th day of May, 1928.
